UNITED STATES PATENT OFFICE

HARRY H. BARBER, OF AURORA, ILLINOIS, ASSIGNOR TO BARBER-GREENE COMPANY,
OF AURORA, ILLINOIS, A CORPORATION OF ILLINOIS

DIGGING BUCKET

Application filed June 25, 1931. Serial No. 546,847.

This invention relates to a digging bucket for ditching machines and concerns itself more particularly with the cutting elements and the manner of securing the same to the bucket.

The cutting elements for such buckets are usually made of some expensive material that will maintain a good cutting edge for a reasonable time before they have to be replaced.

10 In the past these cutting elements have been subjected to considerable bending strains that frequently distorted the same. Moreover, considerable difficulty has been encountered in replacing the cutting elements.

15 It is an object of this invention to overcome the above noted objections in the provision of less expensive cutting elements that may be more readily and frequently replaced, and that eliminate to a great extent the previous 20 tendency to bend, and wherein the cutting force results mainly in a compression action.

The invention comprises the novel structure and combination of parts hereinafter described and more particularly pointed out 25 and defined in the appended claims.

In the accompanying drawing which illustrates a preferred form of this invention and in which similar reference numerals refer to similar features in the different views:

30 Figure 1 is a top plan view of a digging bucket equipped with cutting elements involving this invention;

Figure 2 is an enlarged top plan view of one of the cutting elements;

35 Figure 3 is a sectional view taken upon the line III—III of Figure 1 looking in the direction of the arrows; and

Figure 4 is an enlarged sectional view taken upon the line IV—IV of Figure 2 looking 40 in the direction of the arrows.

Describing the invention in relation to the drawing, there has been illustrated a digging bucket 1 provided with a series of cutting elements 2. Each cutting element has a base 45 provided with a slot 5 extending inwardly from the rear edge, and the base portion upon each side of the slot is provided with a rib 3 having upwardly diverging sides that terminate in a horizontal shoulder 4. The cutting or digging portion 2b rises from the

forward portion and sides of the base. The inclined cutting portion 2b is relatively thin in section to present a relatively sharp cutting or digging edge as it is worn. The slope of the cutting portion 2b is such that as it 55 wears its projection beyond the front edge of the bucket does not decrease in direct proportion to the wear. The interior sides of the cutting portion or tooth are bevelled as indicated at 6, while the front part of the tooth inclines forwardly from a point midway of its height as indicated at 2a. The corners that join the sides with the cutting portion 2b are thicker than the cutting portion 2b with the result that they wear down 60 slower and may form a double pick pointed tooth. Due to the construction of the tooth, it will be obvious that the major portion of the force exerted thereon will be of a compressive nature and very little bending force 65 will occur. This compressive force will readily be transmitted to a relatively broad supporting base 7 upon the bucket.

For it will be appreciated that the bevelled portions 6 of the sides slope downwardly toward the center of the tooth thereby increasing the thickness of the base of the side walls and materially reinforcing the same, with the result that bending movement of the tooth will be strongly resisted 75 and more of a compression action will occur.

The bucket has a plurality of such supporting bases 7, one for each tooth. Each base 7 has an angular groove 8 for receiving the angular rib portion 3 of each tooth and centering such tooth and flat portions adjacent said groove for sustaining the shoulders 4 on the tooth. These base portions are provided with apertures for receiving bolts 9 which extend through the slots 5 and which are provided with sufficiently large polygonal heads 10 for overlapping the walls of the slots. It will be noted that the head of each bolt fits between the side walls and against the front wall of the tooth which forms a recess for receiving a portion of each bolt head and prevents rotation thereof, and that the longitudinal axis of the bolt lies substantially parallel to the line of thrust on the tooth. In order to remove a tooth, it is only 100

necessary to loosen its bolt when the tooth may be slid out.

I am aware that many changes may be made and numerous details of construction 5 may be varied through a wide range without departing from the principles of this invention, and I therefore do not purpose limiting the patent granted hereon otherwise than necessitated by the prior art.

10 I claim as my invention:

1. A cutting tooth for a digging bucket having a base portion provided with a centering projection and shoulders adjacent the sides of said projection, said base portion merging in upwardly extending bevelled side walls connected by a forwardly inclined front wall, the construction being such that the cutting action transmits mostly a compressive force with respect to the base.
- 15 2. A cutting tooth for a digging bucket having a base portion with a centering rib and bearing portions adjacent the sides of the rib, said base merging into side walls having inwardly inclined bevelled portions 25 and a front wall having an upper forwardly sloping portion.

3. A cutting tooth for a digging bucket having a supporting base provided with a bevelled centering rib and bearing portions 30 adjacent the sides of said rib, said base having a bolt securing aperture, said base merging in side walls having interior sloping portions and a forwardly sloping front wall.

35 4. A cutting tooth for digging buckets comprising a base portion, a front wall of substantially uniform thickness extending upwardly from the forward portion of the base and terminating in a cutting edge, and tapering side portions extending upwardly 40 from the sides of the base and inclined toward the cutting edge and adapted to reinforce and support the front wall and form

therewith a recess adapted for receiving the head of an attaching member and maintaining the same against rotation.

5. In a digging bucket having a tooth supporting case, a tooth having a base portion resting upon said base, said base portion having a forwardly inclined wall terminating in a cutting edge and bevelled forwardly inclined walls merging into said front wall for reinforcing said front wall, said base portion having an opening, a bolt extending through said opening and base, said bolt having a head and the walls of said tooth forming a recess for receiving said head and preventing rotation thereof, the longitudinal axis of said bolt lying substantially parallel to the line of thrust on said tooth.

6. In a digging bucket having a tooth support, a tooth having a base resting upon said support, said base having a front wall forwardly inclined and terminating in a cutting edge, and tapering side walls merging with said front wall, said side walls and front wall forming a recess, said support and base having an aperture and a bolt 85 having its head located in said recess and extending through said aperture and lying substantially parallel to the line of thrust upon said cutting edge.

7. A tooth for digging buckets, comprising a base having an upwardly extending and forwardly inclined front wall terminating in a cutting edge, and side walls tapering in thickness and width from said base and merging with said front wall, said side walls and front wall forming a recess adapted for receiving the head of an attaching bolt and retaining the same against rotation.

In testimony whereof I have hereunto subscribed my name at Aurora, Kane County, Illinois.

HARRY H. BARBER.
